UNITED STATES PATENT OFFICE

JOHN R. SOUSA, OF WASHINGTON, DISTRICT OF COLUMBIA, ASSIGNOR TO AUTOMATIC ASSORTING MACHINE COMPANY, OF WASHINGTON, DISTRICT OF COLUMBIA, A CORPORATION OF DELAWARE

PARCEL-ASSORTING DEVICE

Application filed December 9, 1927. Serial No. 238,979.

This invention relates to a parcel assorting device, the general object of the invention being to provide a plurality of rows of receptacles for receiving the articles and an electrically operated carriage for each row for taking the parcels from a central point to the receptacles, with rake devices for removing the parcels from the carriages and depositing them into the receptacles and manually operated means for moving any desired rake device into active position, such means also closing the circuit to the motor of the carriage.

Another object of the invention is to provide means for returning each carriage to its starting point, with shock absorbing means for checking the movement of the carriage as it nears the end of its track.

A still further object is to provide each carriage with four trolleys, with a track or wire for each trolley and switch means for controlling the circuits to the trolley wires in such a manner that the carriage is caused to move forwardly when the switch is closed and after the switch is released by the rake operating means, the current to the motor is reversed so that the carriage returns to its starting point, with means for stopping the carriage adjacent the end of the track if a rake device should remain in active position.

A still further object is to provide extensions on the receptacles so that the parcels deposited therein can be moved into the extensions, thus leaving the receptacles free to receive other parcels.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a plan view of portion of the invention.

Figure 2 is an elevation.

Figure 3 is a section on line 3—3 of Figure 1.

Figure 4 is a transverse sectional view through portion of a track and showing an end view of the carriage.

Figure 5 is a view looking in the opposite direction from Figure 4.

Figure 6 is an elevation of the carriage, with portions of the supporting means in section.

Figure 7 is a plan view of the carriage.

Figure 8 is a front view of a part of the device, showing a row of keys and the identifying means for the receptacles in the row.

Figure 9 is a plan view of Figure 8, with part of the front in section.

Figure 10 is a side view of Figure 8.

Figure 11 is a view of the contacts of the switch.

Figure 12 is a section on line 12—12 of Figure 13.

Figure 13 is a section on line 13—13 of Figure 12.

Figure 14 is a sectional view through the shock absorbing means.

Figure 15 is a side view of portion of such means.

Figure 16 is a view of the latch for holding each gate means in raised position.

Figure 17 is a plan view of Figure 16.

Figure 18 is a view showing how the latch holds the gate in raised position.

Figure 19 is a perspective view showing how the cables are attached to the rake means and the switches.

Figure 20 is a sectional view showing how the trolley is yieldably held in raised position.

Figure 21 is a diagrammatic view of the circuits.

In these views, A indicates a framework which supports a number of horizontal rows of receptacles 1, each receptacle being provided with an extension 2 which projects beyond the framework so that articles deposited into the receptacle may be pulled into the extension and thus leave the receptacle free to receive other articles. A track 3 is arranged above each row of receptacles to support the wheels of a carriage B so that each carriage

will pass above the tops of each row of receptacles. Each carriage has its parcel carrying portion formed of spaced fingers 4 upon which the parcels rest and each carriage is driven by a motor M, the shaft of which is connected by the gears 5 with the shaft 6 of the carriage to which some of the supporting wheels 7 are connected. Four trolley wires a, b, c and d are arranged above each row of receptacles, these wires being attached to the insulators 8 and trolley wheels 9, 10, 11 and 12 engage the wires and each wheel has its harp 13 pressed upwardly in a socket member 14 by a coil spring 15 so that each wheel is yieldingly held in engagement with its wire. Each harp is electrically connected with the motor, as shown in Figure 7. The wires a and b are contacted by the trolley wheels which are connected with the field of the motor, while the wires c and d are contacted by the wheels which are connected to the armature of the motor.

Adjacent the front end of the track, the wire c is separated by an insulated portion c', while adjacent the rear end of the track, the wire d is separated by an insulated portion d'. The front insulated section of wire c is connected to wire b, as shown at b'. A switch S, comprising four contacts 16, 17, 18 and 19, and a switch arm 20 which carries a pair of contacts 21 and 22, controls the flow of current from the main switch 23 to the trolley wires. A conductor 24 connects the positive contact of the main switch 23 with the contact 21 of the switch arm and a conductor 25 connects the negative contact of the switch 23 with the trolley wire a. Contacts 16 and 18 are connected together by the conductor 26 and contacts 17 and 19 are connected together by the conductor 27. A conductor 28 connects contact 16 with trolley wire d and a conductor 29 connects contact 19 with trolley wire c. A conductor 30 connects contact 22 of the switch arm 20 with trolley wire b and with that part of wire d beyond the insulated part d'.

With the carriage at the front end of the track and the switch 20 in its normal position with its contacts against the contacts 18 and 19, no current will pass to the motor of the carriage as the current is interrupted by the insulated part c' of wire c. However, when the switch arm 20 is moved against the contacts 16 and 17, current will flow from the main line over conductor 24 through contacts 21 and 16, conductor 28 to trolley wire d through the trolley wheels, contact wires c and d over branch b' to the wires a and b and through the return conductor 25 to the negative of the main line. Thus the motor will be rotated in a direction to cause the carriage to move forwardly over the track and this movement will continue as long as the switch arm 20 remains against the contacts 16 and 17. When the switch arm 20 is moved back to

its original position against the contacts 18 and 19, current will then flow from the conductor 24, contacts 21 and 19, conductor 29 to the trolley wire c through the trolley wheels, contacting the wires c and d, over trolley wire d, conductor 28, contact 16, conductor 26 to contact 18 and over conductor 30 to the field wires a and b and through trolley wheels and over return conductor 25. Thus the current through the armatures may be reversed and the motor will cause the carriage to return to its starting point. As soon as the carriage passes beyond the insulated part c', the current to the motor will be broken.

If the switch arm 20 should remain in contact with the contacts 16 and 17 until the carriage passed over the insulated part d', current to the motor of the carriage would be broken by said part d' so that the carriage would come to rest. Then as soon as the switch arm 20 returned to its normal position against the contacts 18 and 19, current would again flow to the motor of the carriage but in an opposite direction to the armatures thereof so that the motor would return the carriage to the front end of the track.

A rake device 31 is pivoted in each compartment, with its prongs adapted to pass between the fingers of the carriage, when the rake device is in raised position to cause the parcels in the carriage to drop from the carriage into the receptacle. Each rake device is provided with an arm 32 to which is attached a cable 33 and each cable is also attached at its rear end to a lever 34 pivoted in a case 35 in which is also pivoted the switch arm 20 and in the bottom of which are arranged contacts 16, 17, 18 and 19, a coil spring 36, attached to the switch arm 20 and to a part of the case, holding the switch arm in a position with its contacts against the contacts 18 and 19. Thus it will be seen that when a cable is pulled upon to raise the rake device, it will also operate a lever 34 to move the switch arm 20 against the action of its spring 36 to cause its contacts to engage the contacts 16 and 17.

Each cable is connected at its front end to a bell crank 37, and each bell crank 37 is connected by a link 38 with a long arm of a bell crank 39 arranged in a frame 40 at the front of each row of receptacles, and the short arm of each bell crank 39 is adapted to be engaged by the short arm of a bell crank 41 having a part projecting through a slot in the front end of the frame 40, with a key 42 on the end of this projecting part. These key bell cranks are each pivoted to a rod 43 fastened to the inner face of the front of the frame 40. Thus by pushing upon one of the keys 42, the bell crank 41 thereof will be depressed and its short arm will rock the bell crank 39 with which it engages and this bell crank, through the link 38, will rock the bell crank 37 with which the link is connected and thus

a pull will be exerted upon the cable 33 attached to the bell crank 37 so that the rake device with which the cable is connected will be raised, and at the same time a lever 34 will be operated to move the switch arm 20 against the contacts 16 and 17. As the rake device is raised, a long prong 44 thereof will engage a latch 45 pivoted to a bracket 46 attached to a part of the frame A and thus the switch arm 20 will be held in raised position even though the finger is removed from the key 42. The latch will not only hold the rake device in raised position, but it will also hold the switch arm against the contacts 16 and 17. As before stated, this position of the switch arm 20 will cause current to flow to the motor of the carriage at the front of the row of receptacles so that the carriage will move forwardly until it reaches the rake device which is in raised position. The prongs of the rake device will pull the articles from the carriage and deposit them in the receptacle and as the carriage passes the rake device, a cam 47 thereon will strike a projecting part 48 of the latch 45, raising the same so that the latch will release the rake device and permit the rake device to drop back to its normal inactive position. This will slacken the cable 33 which is attached to the rake device so that the spring 36 will return the switch arm 20 to normal position against the contacts 18 and 19, thus reversing the flow of current to the motor of the carriage so that the carriage will return to its starting point. As before stated, as the carriage passes over the insulated part, the circuit of the motor will be broken, and thus the carriage will come to rest at the front of the device. If the rake device should fail to drop to its inactive position, the carriage would proceed to the end of the track where it would pass over the insulated part d', which would break the circuit to the motor of the same and thus the carriage would come to rest at the end of the track. Then when the switch was reversed, the carriage would return to its starting point.

Thus it will be seen that the operator, by depressing a key 42, can have the carriage pass to any desired compartment and deposit the laundry therein and then the carriage will return to its starting point, it simply being necessary for the operator to depress the proper key. Identification means for each key may be arranged at the front of the apparatus under each row of keys, as shown at 49.

I provide shock absorbing means for checking the movement of the carriage as it nears the front end of the track on its return movement, such means comprising an endless chain 50 carried by the sprockets 51 on the shafts 52 which are suitably supported in the frame, a projection 53 on the chain being connected by a rod 54 with the piston 55' of a

dashpot 55, the exhaust passage 56 of which is regulated by a set screw 57. The carriage carries a projection 58 which is adapted to strike the projection 53 as the carriage nears the limit of its return movement so that the dashpot arrangement acts as a check to the movement of the carriage and gradually brings the same to a stop upon the insulated portion of the trolley wires. In order to return the piston of the dashpot to its original position, I provide a second projection 59 on the endless chain which is in front of the projection 53 and which is provided with a pivoted arm 60. As the carriage moves forwardly from the front of the device, it will strike this arm 60 which is held against movement by the projection 59 so that the chain is moved and the piston of the dashpot moved to its normal position. As the projection 59 and its arm start to pass over one of the sprockets 51, the arm 60 will pass beyond the path of the projection 58 of the carriage and thus the endless chain will come to rest. If the projection 59 and its arm should return into the path of the projection 58 on the carriage, then said projection 58, on the return movement of the carriage, would simply strike the arm 60 and move the same on its pivot until the projection 58 passed beyond the same and thus the projection 58 can engage the projection 53 on the endless chain without interference on the part of the projection 59 and its arm 60.

Instead of using the receptacles, as shown, sacks can be suspended from hooks on the frame to receive the articles raked from the carriage and the first receptacle or compartment in each row and some of the last ones in each row can have their rake devices omitted so as to insure the proper operation of the carriages.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. A distributing machine comprising a plurality of receiving compartments, a carriage for conveying articles thereto, means for conveying the articles from the carriage to the compartments, manually operated means for moving any desired conveying means into active position including mechanical connections between the operating means and the conveying means, a motor for driving the carriage, circuits for the same and means operated by the manually operated means including mechanical connections between the conveying means and such means for causing the motor to drive the carriage forwardly to the compartment, the conveying

means of which has been moved into active position and for reversing the circuit after the carriage has passed the compartment to cause the carriage to return to its starting point.

5. 2. A distributing machine comprising a plurality of receiving compartments, a carriage for conveying articles thereto, transfer means at each compartment for transferring articles from the carriage to the compartment, key operated means for actuating the transferring means such means including mechanical connections between the keys and the transferring means, a motor for operating the carriage, circuits for the same, a switch for controlling the circuits and means connected with the key operated means for moving the switch and including mechanical connections between the switch and the transferring means.

10. 3. A distributing machine comprising a plurality of receiving compartments, a carriage for conveying articles thereto, transfer means at each compartment for transferring articles from the carriage to the compartment, key operated means for actuating the transferring means, a motor for operating the carriage, circuits for the same, a switch for controlling the circuits, means connected with the key operated means for moving the switch, and shock absorbing means for retarding the movement of the carriage to its starting point.

15. 4. A distributing machine comprising a plurality of receiving compartments, a carriage for conveying articles thereto, transfer means at each compartment for transferring articles from the carriage to the compartment, key operated means for actuating the transferring means, a motor for operating the carriage, circuits for the same, a switch for controlling the circuits, means connected with the key operated means for moving the switch, shock absorbing means for retarding the movement of the carriage to its starting point, such means comprising an endless chain, sprockets for supporting the same, a projection on the chain, a rod connected with the projection, a dashpot and a piston in the dashpot to which the rod is connected and a part of the carriage engaging the projection on the chain when the carriage nears the end of its return movement.

20. 5. A distributing machine comprising a plurality of receiving compartments, a carriage for conveying articles thereto, transfer means at each compartment for transferring articles from the carriage to the compartment, key operated means for actuating the transferring means, a motor for operating the carriage, circuits for the same, a switch for controlling the circuits, means connected with the key operated means for moving the switch, shock absorbing means for retarding the movement of the carriage to its starting

25. point, such means, comprising an endless chain, sprockets for supporting the same, a projection on the chain, a rod connected with the projection, a dashpot, a piston in the dashpot to which the rod is connected and a part of the carriage engaging the projection on the chain when the carriage nears the end of its return movement and a pivoted projection on the chain adapted to be engaged by a part on the carriage on the forward movement of the carriage for returning the piston in the dashpot to its normal position.

30. 6. A distributing machine comprising a plurality of receiving compartments, a carriage for conveying articles thereto, a rake device at each compartment for conveying articles from the carriage to the compartment, manually operated means for moving any desired rake device to active position, latch means for holding the rake device in active position after being moved to such position by the manually operated means, means on the carriage for releasing the latch means as the carriage passes by the same, a motor for operating the carriage, circuits for the motor including four trolley wires, a trolley assembly for each wire, a switch having two contacts thereon, four stationary contacts arranged in pairs, spring means for normally holding the switch with its contacts against two of the stationary contacts, means connected with the rake devices for moving the switch against the action of its spring to bring its contacts against the other pair of stationary contacts, means for connecting one of the contacts on the switch to a source of supply, means for connecting the field trolley wires with the negative of said source, means for connecting one of the stationary contacts with an armature trolley wire and the opposite stationary contact with the other armature wire, means for connecting the second contact of the switch with one of the field wires and one of the armature wires, an insulated part adjacent the front end of one of the armature wires, an insulated part adjacent the rear end of the other armature wire and a branch connecting the front insulated portion of the armature wire with a field wire.

35. In testimony whereof I affix my signature.
JOHN R. SOUSA.
